Lockwood Johnson
ATTORNEY.

UNITED STATES PATENT OFFICE.

GILBERT A. BARTHOLOMEW, OF FORT WAYNE, INDIANA, ASSIGNOR TO THE NOBLE HEATER COMPANY, OF FORT WAYNE, INDIANA, A CORPORATION.

DESIGN FOR A FOOTREST AUTO-HEATER CASING.

56,579.

Specification for Design.

Patented Nov. 16, 1920.

Application filed March 28, 1920. Serial No. 369,107. Term of patent 14 years.

To all whom it may concern:

Be it known that I, GILBERT A. BARTHOLOMEW, a citizen of the United States, residing in the city of Fort Wayne, county of Allen, and State of Indiana, have invented a new, original, and ornamental Design for a Footrest Auto-Heater Casing, of which the following is a specification, reference being had to the accompanying drawings, forming part thereof.

In the drawings, Figure 1 is a perspective view of my foot rest auto heater casing, and Fig. 2 is an end elevation thereof.

I claim:

The ornamental design for a footrest auto heater casing, as shown.

GILBERT A. BARTHOLOMEW.
